UNITED STATES PATENT OFFICE.

JULIUS C. ANDRESEN AND HENRY F. MARTEN, OF SAN FRANCISCO, CALIFORNIA, AS-SIGNORS TO CALIFORNIA BARREL COMPANY, OF SAN FRANCISCO, CALIFORNIA, A CORPORATION OF CALIFORNIA.

ATTACHING DEVICE FOR RECEPTACLE BAILS.

Application filed March 25, 1926. Serial No. 97,287.

Our invention relates to the class of fastening devices for attaching bails to receptacles.

It is often desirable, and in some cases 5 imperative, that no metallic surface be exposed within the receptacle. This is true particularly of vessels in which soya is packed. These vessels are wooden pails or buckets; and packers decline their use if 10 any metal is exposed within. The common bail fasteners, therefore, which comprise metallic studs, rivets, bolts, pins, staples and the like, passing through the staves to the interior of the vessel are unavailable.

15 The special object of our invention is to meet this difficulty; and this we accomplish by providing a novel bail-attaching device, no part of which is exposed to the interior of the vessel.

20 Although this object finds its special use in thus avoiding interior metallic exposure, it is to be understood that our invention, without regard to and aside from such object, contemplates the provision of a simple, 25 effective and strong bail-fastening, functioning not only to carry the vessel, but also to tighten its stave assembly.

With these objects in view our invention 30 consists primarily of a bail-fastening assembly comprising a suspension member, a vessel-embracing hoop with which one end of the suspension member is connected, and a bail-member with which the other end of the suspension member is connected.

35 It further consists in said assembly when applied to a vessel of inverted frustum shape, the embracing hoop of which assembly tends to tighten under the load.

It consists further in the novel structure 40 of the suspension member, its disposition with relation to the exterior surface of the vessel, and its engagement with the hoop, all of which we shall hereinafter fully describe by reference to the accompanying drawings, 45 it being understood that changes in detail and arrangement may be made without departing from the spirit of our invention as defined by the claims hereunto annexed.

In the drawings—

50 Fig. 1 is a view in elevation of a vessel with our invention applied thereto. Fig. 2 is a sectional view of a stave longitudinally of the kerf. Fig. 3 is a view in elevation of the suspension member. Fig. 4 is a sectional

view on line 4—4 of Fig. 2. Fig. 5 is a view 55 similar to Fig. 4 with a hoop overlying the kerf. Fig. 6 is a transverse section taken on line 6—6 of Fig. 7. Fig. 7 is a view in detail of one of the suspension members received in the kerf, hooked around the stave, 60 and connected with the bail.

1 is a vessel composed of staves with chined-in heads as usual. In the form shown, the vessel has the shape of an inverted cone-frustum, so that its embracing hoops 65 2 tighten by being driven upwardly.

3 is the bail. 4 is the suspension member of our fastening assembly. It consists of a metallic link slightly arcuate in its length, and provided with an eye 4' on its upper 70 end and with a hook 4'' on its lower end.

In the exterior of opposite staves, near their upper ends, and traversing the plane of the uppermost hoop 2, is made a kerf 5 which is arcuate, being deepest at its 75 middle, its ends merging in the surface of the stave. This kerf is relatively shallow and does not extend through the stave.

In assembling the fastening, the suspension link 4 which initially is not bent to form the lower end hook 4'', is passed down within the kerf 5, behind the hoop 2 until the eye 4' of said link rests upon the upper edge of the hoop; and by reason of the arcs of both kerf and link the lower end of the 85 link readily emerges from the kerf below the hoop, and said end is then conveniently bent outwardly and upwardly to form the hook 4'' which engages the hoop, and thus the link is tightly seated on the hoop, by its 90 eye and hook. With the eye of the link, the bail 3 is engaged.

It will now be seen that the load is carried by the hoop, and that when the vessel is of the shape shown the hoop is tightened 95 under the load. It will also be seen that no part of the bail-fastening is exposed within the vessel; and, finally, it is noted, that the fastening is one which can readily be applied, and is efficient.

100 We claim:—

1. In combination with a receptacle having on its exterior at opposite sides a kerf, with a depth less than the thickness of the receptacle wall, an embracing hoop crossing said kerfs, a bail member, and a suspension link seated in each of said kerfs behind the hoop, said links each provided on its upper 105

end with an eye for resting on the upper edge of the hoop and each at its lower end engaging the lower edge of the hoop, and the eyes receiving the bail member, said 5 grooves and said links being arcuate.

2. In combination with a receptacle having on its exterior at opposite sides a kerf, with a depth less than the thickness of the receptacle wall, an embracing hoop crossing 10 said kerfs, a bail member, and a suspension

link seated in each of said kerfs behind the hoop, said links each provided on its upper end with an eye for resting on the upper edge of the hoop and each at its lower end engaging the lower edge of the hoop and 15 the eyes receiving the bail member.

In testimony whereof we have signed our names to this specification.

JULIUS C. ANDRESEN.
HENRY F. MARTEN.
